UNITED STATES PATENT OFFICE.

HUGO GOLDSMITH, OF CINCINNATI, OHIO, ASSIGNOR, BY MESNE ASSIGNMENTS, TO THE P. GOLDSMITH SONS COMPANY, OF CINCINNATI, OHIO, A CORPORATION OF OHIO.

ATHLETIC PROTECTIVE GARMENT.

Application filed March 27, 1922. Serial No. 547,136.

To all whom it may concern:

Be it known that I, HUGO GOLDSMITH, a citizen of the United States of America, and a resident of Cincinnati, in the county 5 of Hamilton and State of Ohio, have invented a new and useful Improvement in an Athletic Protective Garment, of which the following is a specification.

My invention relates to protective garments of the type generally employed by 10 participants in such games as football, soccer, etc.

I have shown my invention as applied to a head guard or helmet although it is 15 readily apparent that same may be readily applied to other protectors employed on other parts of the body.

An object of my invention is to provide 20 a device of the type referred to, which will afford a maximum of protection to the wearer.

Another object of my invention is to provide 25 a device of this kind, which will serve to minimize the shock of impact.

Another object of my invention is to provide 30 a device of the type referred to which is simple in construction and which may be readily assembled.

These and other objects are obtained by 35 means described herein and disclosed in the accompanying drawings, in which:

Fig. 1 is a perspective view of a helmet embodying my invention.

Fig. 2 is a longitudinal sectional view of 40 a device such as that shown in Fig. 1.

The helmet 3 comprises a leather outer casing or covering 4, which is preferably of a tough and stiff nature. Any other material may be employed for this cover-

45 ing, although leather is preferable. Cross straps 5 and 6 in the nature of leather bands, extend over the outer face of the casing 4 and may be secured thereupon in any suitable manner such as by rows of stitching 7. A lining pad 8 preferably of felt is secured upon the inside of the leather casing by any suitable manner such as by being sewed thereto by rows of stitching 16. The pad 8 and the leather casing have a series of registering perforations 9 whereby ventilation of the interior of the garment is obtained. A rubber ring 10 preferably of a resilient sponge rubber is secured upon the inner surface of the pad 8, by any suitable means such as by bands 11 of tape or other

suitable material, extending about the ring and thru perforation 12 in the pad 8, perforations 12 being in the nature of the ventilation perforations heretofore referred to. The tape band preferably does not extend 60 thru any perforations in the leather casing. The rubber band is preferably made of such size and shape that it will readily accommodate itself to the head of the wearer, and is therefore made somewhat elongated. Any 65 other suitable means to secure the ring upon the garment may be employed. Helmets of the type disclosed are generally provided with ear laps 13 and 14, the lower ends of which are connected by an elastic band 15 70 whereby the device may be retained on the head of the wearer. When any force of impact is directed upon a helmet, or other garments made in conformity with the invention herein disclosed, the casing 4, the 75 pad 8, and the sponge rubber ring 10, co-operate in meeting said force. The ring 10 being of a sponge rubber, precludes any sharp and decided impact from being immediately transmitted to the head of the wearer, such ring serving to yieldingly resist the impact, while at the same time the subconscious reaction of the player musters the energy and strength of the player to the resistance of the impact before the full 80 force of such impact is directed upon the player. The leather casing serves as a protecting casing to the pad and to the rubber ring and protects same against any sharp or cutting edges which might ordinarily come in contact therewith, and also protects the player. The pad is somewhat resilient and serves as a buffer having a soft finish which will not injure or scratch the wearer.

What I claim is:

1. A protective athletic helmet, comprising a leather casing for fitting over the wearer's head, and provided with means for detachably securing the same on the head, a felt lining contacting with the interior of the casing, and a resilient rubber ring of smaller diameter than the wearer's head, and located upon the inside of the lining at the top of the helmet, and for contacting with the top of the wearer's head, and for yieldingly spacing the lining from the wearer's head whereby to normally provide a ventilating air space between the lining and the wearer's head and through which space the wearer's head may move for con- 105

tacting the lining when a blow is directed upon the helmet.

2. In a foot ball helmet the combination with a leather casing for fitting over a wearer's head, and provided with a crown portion and with means for detachably securing it upon the head, a resilient rubber ring of smaller diameter than the wearer's head and carried within and at the crown 10 of the helmet for engagement with the top of a wearer's head and for yieldingly spac-

ing the casing therefrom whereby to normally provide a ventilating air space between the lining and the wearer's head and through which space the wearer's head may move for contacting the lining when a blow is directed upon the helmet.

In testimony whereof, I have hereunto subscribed my name this 25th day of March, 1922.

HUGO GOLDSMITH.
